UNITED STATES PATENT OFFICE.

JOSEPH JOUBERT, OF DOIZIEU, FRANCE, ASSIGNOR TO THE MACHINE-FACTORY RÜTI, FORMERLY CASPAR HONEGGER, OF RÜTI, SWITZERLAND.

MACHINE FOR DRAWING IN WARP-THREADS.

SPECIFICATION forming part of Letters Patent No. 622,154, dated March 28, 1899.

Application filed April 1, 1898. Serial No. 676,135. (No model.)

To all whom it may concern:

Be it known that I, JOSEPH JOUBERT, a citizen of France, residing at Doizieu, in the Department of Loire, France, have invented 5 certain new and useful Improvements in Machines for Drawing in Warp-Threads, of which the following is a specification.

The present invention has for its object the drawing of the warp between the teeth of the 10 slay by mechanical means and to effect the same with automatic regulation from tooth to tooth continuously. Hitherto the eye and hand of the operator occupied with the so-called "drawing" or "slaying" of the threads 15 have been exercised to effect, with painful regularity of control, the action of the warp-hook in order that the same may regularly advance from one passage of the hook to another exactly for one tooth, (not more and not 20 less.) In this case the operating of the hook, the drawing back of the same, and the following advance of one tooth are effected absolutely mechanically and without possibility of failure.

25 In the accompanying drawings the invention is illustrated.

Figure 1 shows a plan of the drawing organs. Figure 2 shows an end view of the apparatus; Fig. 3, a front elevation of the same; 30 Fig. 4, a detailed lateral view of the drawing organs on a somewhat larger scale, and Fig. 5 a diagram of the adjustments thereof. Fig. 6 is an end view of the machine with the actuating mechanism. Fig. 7 is a front view of 35 the same; and Fig. 8 is a section following the line $\alpha\alpha$, Fig. 2.

The letter a indicates the slay. The lower portion of the slay-frame is fitted into and held by the longitudinal groove of a cross-bar 40 a' , (see Figs. 2, 6, and 7,) fixed to the standard of the machine.

The principal organs of the machine for drawing in warp-threads are as follows: The warp-hook b , the counter-plate c , resting 45 lightly against its point, and the plate d , which accompanies the warp-hook b and rests lightly upon the plate c . The part c (see Fig. 2) is rigid, and the parts b and d are pivoted. They stand opposite one another, fixed upon

a slide e , which moves in the frame $f f'$ and 50 which is moved to and fro by a toothing e' on its under surface, which engages in a gear-wheel g . The frames $f f'$ are carried by the jointed arms $h h' h^2 h^3$. Every two of these arms, which are placed upon the same side of 55 the screw-spindle i , are connected by bolts $j j'$ $j^2 j^3$ above and by bolts $j^4 j^5 j^6 j^7$ below, at the same distance, on the one hand with the traveler k and on the other hand with the frames $f f'$. In this manner are formed two parallelograms, which cause a sidewise motion of 60 the above-mentioned main organs, but at the same time maintain their exactly parallel and vertical position. The traveler k has on each side a roller $l l'$, which rollers impinge upon 65 two bars $l^2 l^3$ parallel with the screw-spindle. The screw-spindle i has a longitudinal groove i' , Figs. 2, 3, and 8, in which the pin m , which is connected with the gear-wheel g , 70 engages, so that at the alternate revolutions of the spindle i the wheel g is always moved with it, and thus the slide e is caused to travel to and fro in its guides $f f'$. By aid of a friction-disk g' , Fig. 8, between the 75 wheel g and the intermediate wheel n the latter is also caused to move correspondingly, excepting when the hook o engages in the teeth of the said wheel n . Then the latter remains standing at the left motion of the slide e , Fig. 2. As, however, a pin p , engag- 80 ing in the thread of the screw-spindle, is connected with the intermediate wheel n , it follows that if the wheel n does not turn while the screw-spindle makes a motion of revolution a certain sidewise displacement of the 85 former will take place in the longitudinal direction of the latter, and consequently also a displacement of the whole traveler, in which the wheel g and the intermediate wheel n are supported concentrically with the screw- 90 spindle.

The hook o forms one arm of an angle-lever, under the other arm q of which one arm s of a second angle-lever r engages. The said arm s has above it a regulating-screw t , 95 against which the frame $f f'$ rests when it moves to the left. (See Fig. 3.) Then, owing to the action of this angle-lever, the hook o

is held away from the teeth of the wheel n , and no motion of the traveler takes place in the longitudinal direction of the screw-spindle. In order that the engagement of the 5 wheel g in the tooth of the frame ff' may always remain correct, even when the frame ff' is pushed to the left or the right and at the same time sinks somewhat downward, the teeth thereof are of a suitable profile of ball 10 shape. The alternating revolving motion of the screw-spindle i can be effected by means of a pedal i^2 , belts i^3 , pulleys i^4 , fixed upon the spindle i , and counter-springs i^5 , i^6 . (See Figs. 6 and 7.)

15 The operation of the principal organs is illustrated in Fig. 5 by four different positions thereof with respect to the slay a , into which the warp is drawn.

First position.—In the tooth-space through 20 which the counter-blade c passes a warp-thread has been drawn in from left to right.

Second position.—The slide, with parts bcd , is moved in the frames ff' from right to left. The accompanying plate d passes, with the 25 plate c , through the same tooth-aperture, while the warp-hook b engages in the tooth-aperture lying next to the right and passes through them.

Third position.—The warp-hook b and the 30 plate d are separated by one tooth. The piece c is out of reach of the slay a . The next following warp-thread is now inserted by hand in the slot u of the hook b .

Fourth position.—The slide, with parts bcd , 35 moves again back from left to right. At this the piece c passes, together with the hook b , through the same tooth-aperture and rests upon the piece b . The piece d permits the tooth, which is between itself and the hook 40 b , to pass out and then rests on the further motion to the right again upon the part c . The motion thus comes again into first position, in which the drawn-in warp-threads are raised by hand out of the slot u and held fast. 45 Then the operation begins anew, because at the next motion to the left of the slide in its guides ff' the hook b enters into the next following tooth-aperture which lies to the right, and so on. As, owing to the continuous motion to the right of the said organs bcd , Fig. 5, the frame ff' is somewhat impelled to the right, Fig. 3, it no longer rests upon the regulating-screw t . The hook o consequently engages in the teeth of the wheel n . This wheel

no longer revolves, and the whole traveler k 55 is consequently moved a little to the right. After this displacement the screw t again comes in contact with the frame ff' , and the hook o is disengaged from the wheel n until, owing to successive motions to the right of the 60 organs bcd , the frame ff' again ceases to rest upon the screw t .

It will be obvious that the pitch of the screw of the spindle i has no importance in relation to the fineness of the slay into which 65 the threads are drawn, but that, on the other hand, in consequence of the intermittent progress of the whole apparatus caused by the motion of the screw-spindle the fine parts—such as the warp-hook, counter-plate, and accompanying plate—have, so to say, no side pressure upon the slay-teeth nor have they to suffer such a pressure from it. The warp-hook b and the accompanying plate d are made capable of being lifted upon the pivot 70 z , Fig. 2, for the purpose of the adjustment at the beginning of the work; also, these parts may conveniently be replaced by other parts serving the same purpose in the case of great differences in the size of the teeth 75 and depth of the teeth.

Having now particularly described and ascertained the nature of my said invention and in what manner the same is to be performed, I declare that what I claim is—

In a machine for drawing in warp-threads, the combination with the warp-hook b , of a spring counter-plate c resting thereon, a plate d accompanying the warp-hook and resting elastically upon the plate c , a slide e carrying the parts b , c , d , provided with a rack e' and supported by links h , a traveler k , a wheel supported therein and capable of being oscillated and axially moved and catching in the rack e' , an intermediate wheel n also supported in said traveler, means for moving and stopping said wheels g and n , and a screw-spindle i carrying the wheels g , n , and screwing the wheel n and the traveler k in lateral direction when the wheel n is stopped in rotation.

In witness whereof I have hereunto set my hand in presence of two witnesses.

JOSEPH JOUBERT.
